UNITED STATES PATENT OFFICE.

CHARLES Y. HAKE, OF YORK, PENNSYLVANIA.

INCUBATOR.

Application filed July 9, 1925. Serial No. 42,567.

My invention relates to improvements in incubators of that type which includes a tray removably supported within a casing having a plurality of rollers for supporting eggs 5 within the case in proximity to a source of heat.

The invention consists in the combinations, constructions, and arrangements herein described and claimed and contemplates 10 the provision of a novel means for transmitting motion to the rollers of the tray when desired when the tray is in place within the case.

A further object of the invention is the 15 provision in an incubator of the class described of means adapted to be actuated at the outer side of the incubator case to cause turning of the rollers of the tray within the case when desired without causing any obstruction to be placed in the front part of 20 the incubator case which might tend to cause injury to the chicks within the lower part of the incubator case when a tray is withdrawn from the incubator case at the back of 25 the latter.

A still further object of the invention is the provision in an incubator of the character described of a tray having rollers for supporting eggs and having motion transmitting means on the opposite end portions 30 of the rollers adapted to engage with cooperating means on a bar which is slidable through the rear part of the incubator chamber transversely of the incubator chamber, the motion transmitting elements on the ends 35 of the rollers at the inner end of the tray being adapted to be automatically moved into engagement with the cooperating elements on the slideable bar when the roller 40 tray is moved longitudinally in a horizontal plane to position within the incubator chamber, no tilting of the inner end of the roller tray being necessary to insure engagement 45 of the motion transmitting means on the rollers with the cooperating elements on the bar for turning the rollers when the roller tray is pushed to position in the incubator compartment and the roller tray being horizontally disposed at all times.

50 Other objects and advantages of the invention will be apparent from the following description, considered in conjunction with the accompanying drawings, in which—

55 Figure 1 is a perspective view of a portion of an incubator casing sufficient to show an incubator compartment within the casing for

the reception of a roller tray and such other trays as may be used in connection with the hatching of chicks, a portion of the side wall of the compartment being broken away 60 to show a roller tray within the compartment.

Figure 2 is a longitudinal vertical section through the structure exhibited in Figure 1, showing in full lines the roller tray within 65 the incubator compartment and showing in dash lines a fragmentary portion of the tray partially withdrawn from position in the incubator compartment.

Figure 3 is a view similar to Figure 2 with 70 the roller tray omitted and with a screen bottomed hatching tray in place within the incubator compartment,

Figure 4 is a perspective view of the roller 75 tray.

Figure 5 is a perspective view of the hatching tray,

Figure 6 is a vertical section through an end portion of a roller and through a bar for turning the rollers, showing in elevation 80 a bevel gear on the roller in mesh with inclined teeth on the bar, and

Figure 7 is a fragmentary vertical section substantially along the line 7—7 of Figure 85 2, looking in the direction of the arrows.

An incubator to be equipped with the invention may have a case which may comprise a top 1, a back wall 2, a bottom 3, and such vertical side walls 4 as may be required to divide the space within the case 90 transversely to produce within the case one or more incubating compartments, such as indicated at 5. A door 6 is swingingly attached to a stationary portion of the case, as for example at its lower edge by a hinge 95 or hinges such as indicated at 7, there being a door 6 for each incubator compartment 5. Each door 6 is swingable to and from position to close the associated incubator compartment 5 at the front of the latter. 100

A pair of horizontal supporting strips 8 are provided for each compartment 5, the respective supporting strips 8 being secured by fastening devices 9 to the side walls 4 of the compartment so that the upper edges 105 of the casing are in the same horizontal plane, which is located intermediate the height of the incubator compartment. The strips 8 extend for substantially the full length of the side walls 4 but terminate at 110 their forward ends slightly short of the forward ends of the side walls 4 and against

vertical strips 10 which are secured by fastening devices 11 to the side walls 4 and have the upper end portions thereof, as at 12, extending above the plane of the upper edges 5 of the horizontal supporting strips. The side walls 4 are provided with aligned openings 13 which are located adjacent to the rearward ends of the side walls 4. The openings 13 extend above the level of the 10 upper edges of the supporting strips and suitable slots or openings may be provided in the strips, as at 14 in Figure 2 to permit a rack bar 15 to be slid through the openings 13 and the slots or openings 14 in the 15 strips 8 transversely across the rearward part of the incubator compartment 5. The upper edge portion of the rack bar 15 extends above the plane of the upper edges of the supporting strips 8 and is formed 20 with teeth 16 which are inclined downwardly and forwardly.

A roller tray for supporting eggs within the compartment 5 in proximity to a source of heat, which may be the spaced 25 steam pipes 17 in the upper part of the compartment 5, is shown to advantage in Figure 4 and is generally designated 18. The tray 18 may comprise a pair of side members 19 and a pair of spaced parallel 30 end members 20 which connect the side members 19 and hold the latter in spaced parallel position. A plurality of rollers 21 are disposed in spaced parallel relation to one another between the end members 20 35 and may have journal portions, as at 22, at the opposite ends supported in bearings on the end members 20 of the roller tray. Bevel gears 23 are secured on opposite end portions of each roller 21 and the journal 40 portions 22 hereinbefore mentioned may be integral with the bevel gears as shown in Figure 6. The teeth on each bevel gear 23 are inclined to be complementary to the teeth on the rack bar 15. The width of the roller 45 tray 18 is slightly less than that of the compartment 5 so that the roller tray is adapted to be extended through the open end of the compartment 5 when the door 6 thereof is open to and from position to slide on 50 the supporting strips 8 to the position shown by the full lines in Fig. 2, the tray 18 sliding on the upper edges of the strips 8 and the bevel gears 23 at the inner end of the tray moving into position to engage the teeth on 55 the rack bar 15 as the tray is moved from the dotted line position of Figure 2 inwardly of the compartment along the strips 8 to the full line position of Figure 2. It is not necessary that the inner end of the tray 18 be 60 tilted in order to insure engagement of the gears at the inner end of the rollers with the teeth of the rack bar 15 since the complementary beveling of the teeth of the rack bar and the associated gears on the rollers 65 permits the tray 18 to be slid horizontally

on the strips 8 until the gears 23 at the inner ends of the roller tray are in mesh with the teeth on the transversely extending rack bar 15. When the tray is in this position, the extending upper end portions 12 70 of the strips 10 will enter notches 24 in the side members 19 of the tray 18 adjacent to opposite end portions of the side members and at the lower edges of the side members. The engagement of the extending end portions 12 of the vertical strips 10 will positively prevent retrograde movement of the tray from the position shown by the full lines in Figure 2 and since the tray will remain horizontal and rest on the 80 horizontal strips 8, it will be firmly supported within the compartment 5 with all eggs (not shown) which may rest on the rollers equi-distant from the steam pipes 17 in the upper part of the compartment 5. 85 The notches 24 are provided in the lower edges of the side members 19 adjacent to the opposite ends of the latter and since the bevel gears 23 are provided on opposite ends of the rollers 21 it will be manifest that the tray may be reversed end for end when desired since it is immaterial which of the opposite ends of the tray is inserted first through the opening at the front of the compartment 5 when the tray is slid on 90 the supporting strips 8 to position within the compartment 5.

It is also to be observed at this point that the width of the toothed upper portion of the rack bar 15 is considerably greater than that of the toothed portion of each of the associated bevel gears 23 so that longitudinal movement of the tray or such lateral warping or bending of the rack bar as are likely to take place accidentally or as a result of 100 variations of temperature when the device is in use will not result in the teeth of the associated bevel gears and rack bar moving out of engagement with each other.

The operation of an incubator of the type 110 partially illustrated in Figure 1 is substantially as follows: The eggs are placed on the rollers 21 and the rollers are actuated each day by means of the roller turning rack bar until the period of incubation has nearly 115 expired or in other words until about the 18th day after the eggs were placed on the rollers. The roller tray with the eggs thereon then is withdrawn from the incubator compartment 5 and the eggs are placed on the foraminous bottom 25 of a hatching tray, indicated generally at 26. The hatching tray 120 26 has side members 27 and end members 28 similar to the side members 19 and the end members 20 respectively, of the roller tray, and may be slid on the supporting strips 8 to and from position within the incubator chamber. The hatching tray is 125 shown in position within the incubator compartment in Figure 3 and the side members 130

27 have notches in their lower edges adjacent to the outer ends of the side members as indicated at 29 for engaging with the extending upper end portions 12 of the strips 5 10 at the outer ends of the strip 8. The foraminous bottom 25 terminates short of the outer end of the tray 26, leaving an opening indicated at 30. In practice, the chicks remain on the foraminous bottom 25 10 of the hatching tray after they have been hatched for a time sufficient to permit them to be dried and the opening 30 at that time is closed by a removable cover, not shown. The chicks then move forward on the bottom 15 of the hatching tray 26 and after the cover has been removed from the opening 30, the chicks drop through the opening into a nursery tray 31 which is disposed on the bottom of the compartment 5. An objectionable feature of incubators making use 20 of a roller tray provided prior to the present invention has been that the chicks in the nursery tray can extend their heads up through the opening 30 between the rear edge of the latter and the usual roller turning bar at the forward end of the incubator compartment and therefore extreme care has had to be exercised when removing the hatching tray through the opening at the 25 front of the incubator chamber 5 to prevent 30 injury to the chicks in the nursery tray because of the heads of the chicks being caught between the forward edge of the opening 30 of the hatching tray and the usual roller turning bar in the front part of the incubator compartment. This objectionable feature is obviated when my improved roller tray and roller actuating or turning means are provided in an incubator of the character 35 described since there is no obstruction in advance of the rear edge of the opening 30 of the hatching tray against which the heads of the chicks within the tray can be jammed when the hatching tray is removed 40 from the incubator compartment. Moreover, the roller trays of the present invention can be slid when disposed substantially flatwise on the upper edges of the supporting strip 8 to position to cause engagement of 45 the bevel gears 23 at the inner end of the roller tray with the teeth on the roller turning bar and it is not necessary to tilt one end of the roller tray to insure engaging of gears on the rollers with teeth on a roller 50 turning bar, as has been necessary prior to the present invention. It is not essential to the operation of the device that the teeth on the bevel gears mesh exactly with the teeth on the rack bar. The 55 bevel gears at the inner end of the roller tray will rest on the toothed face of the rack bar and it has been found in actual practice that the engagement of the teeth on the straight rack bar 15 with the teeth on the bevel gears 60 23 which rest on that rack bar will be suf- ficiently intimate and positive to assure turning of the rollers in a substantially smooth and uniform manner when the rack bar is moved longitudinally. Consequently, the eggs which rest on the rollers will be disposed in the same plane and therefore equidistant from the source of heat, such as the steam pipes 17, which may be located in a higher horizontal plane within the incubator compartment. Also, it is not necessary to 70 provide means for supporting the end of the roller tray that has the gears in engagement with teeth of the roller turning bar to prevent undue friction and to prevent accidental displacement of the roller tray in the 75 incubator compartment, as has been usual prior to my invention and should the roller turning bar be warped laterally, as is likely to occur when the same roller turning bar extends through a plurality of juxtaposed 80 incubator compartments for actuating the rollers within all of said compartments at the same time, the roller turning bar of the present invention will not disengage the 85 gears on the rollers since the cooperating teeth on the gears and on the rack bar are complementarily inclined and moreover the rack bar is wider than the toothed portion of each of the gears with which it is associated. 90

Obviously, my invention is susceptible of embodiment in forms other than that illustrated in the accompanying drawing, and I therefore consider as my own all such modifications and adaptations of the form 100 of the device herein described as fairly fall within the scope of the appended claims.

I claim:

1. In an incubator having an incubator compartment formed with an opening at its forward end and having means for removably supporting a tray within the incubator compartment, said tray being movable through the opening at the forward end of the compartment to and from position to be supported within said incubator compartment, bevel gears on the rollers adjacent to the inner end of the tray when said tray is in said incubator compartment, and a rack bar movable longitudinally and extending transversely across said incubator compartment with the teeth on the rack bar in mesh with said bevel gears, whereby said gears and said rollers may be turned in unison. 115
2. In an incubator, a compartment having a pair of vertical side walls, said compartment having an opening at the front thereof, a pair of supporting strips secured on the inner faces of said side walls and extending longitudinally of said compartment, a rack bar extending slidably across the rear part of said compartment, a tray movable through the opening at the forward end of the compartment and slidable on said supporting strips to and from position to be complete- 130

ly disposed within said compartment, said tray having a bottom formed of longitudinally extending parallel rollers, and gears on the inner ends of said rollers in position to engage with the teeth on said rack bar when said tray is moved slidably on said supporting strips to position in said compartment, whereby longitudinal movement of said rack bar will cause turning movement of said rollers in unison, the teeth on said rollers and on said rack bar being complementarily inclined so that the teeth on the rollers will mesh with the teeth on said rack bar when said tray is slid on said supporting strips to position within said incubator compartment.

3. In an incubator, a compartment having a pair of vertical side walls, said compartment having an opening at the front thereof, a pair of supporting strips secured on the inner faces of said side walls and extending longitudinally of said compartment, a rack bar extending slidably across the rear part of said compartment, a tray movable through the opening at the forward end of the compartment and slidable on said supporting strips to and from position to be completely disposed within said compartment, said tray having a bottom formed of longitudinally extending parallel rollers, and gears on the inner ends of said rollers in position to engage with the teeth on said rack bar when said tray is moved slidably on said supporting strips to position in said compartment, whereby longitudinal movement of said rack bar will cause turning movement of said rollers in unison, the teeth on said rollers and on said rack bar being complementarily inclined so that the teeth on the rollers will mesh with the teeth on said rack bar when said tray is slid on said supporting strips to position within said incubator compartment, and vertical strips on the side walls of said incubator compartment at the outer ends of said supporting strips, said vertical strips having portions extending above the upper edges of said supporting strips, said tray having notches in the lower edges of side members thereof adjacent to the outer ends of the side members of the tray for engaging with the extending upper end portions of said vertical strips when said tray is in place in said incubator compartment to prevent accidental longitudinal movement of said tray toward the forward end of said incubator compartment.

40 4. In an incubator, a compartment having a pair of vertical side walls, said compartment having an opening at the front thereof, a pair of supporting strips secured on the inner faces of said side walls and extending longitudinally of said compartment, a rack bar extending slidably across the rear part of said compartment, a tray movable through the opening at the forward end of the compartment and slidable on said supporting strips to and from position to be completely disposed within said compartment, said tray having a bottom formed of longitudinally extending parallel rollers, and gears on the inner ends of said rollers in position to engage with the teeth on said rack bar when said tray is moved slidably on said supporting strips to position in said compartment, whereby longitudinal movement of said rack bar will cause turning movement of said rollers in unison, the teeth on said rollers and on said rack bar being complementarily inclined so that the teeth on the rollers will mesh with the teeth on said rack bar when said tray is slid on said supporting strips to position within said incubator compartment, and vertical strips on the side walls of said incubator compartment at the outer ends of said supporting strips, said vertical strips having portions extending above the upper edges of said supporting strips, said tray having notches in the lower edges of side members thereof adjacent to the outer ends of the side members of the tray for engaging with the extending upper end portions of said vertical strips when said tray is in place in said incubator compartment to prevent accidental longitudinal movement of said tray toward the forward end of said incubator compartment.

45 5. In an incubator, rotary elements, gears associated with the rotary elements for turning said rotary elements, and a rack bar having inclined transverse teeth for engaging with and actuating said gears.

CHARLES Y. HAKE.
